UNITED STATES PATENT OFFICE.

WILLIAM KALTSCHMIDT, OF ERIE, PENNSYLVANIA.

TAPE HOLDER.

Application filed March 10, 1926. Serial No. 93,809.

This invention relates to tape holders for operating tables in hospitals and first aid rooms in shops.

The object of this invention is to provide means to support spools of adhesive tape in convenient position so that it will be available, and can be stripped off of the spool with one hand, and will not be liable to roll off of the table to the floor, and will be kept at all times in a sanitary condition.

For this purpose I have designed a spool holder which is adapted to be suspended upon a side bar of an operating table, and can be moved longitudinally thereon; said holder having a spindle upon which a spool can be placed.

The features of my invention are herein-after fully described and pointed out, and are illustrated in the accompanying drawing 20 in which:

Figure 1 is a side elevation of an operating table, having portions of the supporting legs thereof broken away and showing my invention suspended thereon.

Figure 2 is a transverse section of said table, showing the right hand end of my invention in elevation.

Figure 3 is a like view showing the left hand end of my invention.

Figure 4 is a side elevation of an operating table showing my invention thereon with spools of tape in place thereon.

In these drawings A indicates an operating table, B indicates the legs of the same with portions thereof broken away. C indicates the upper side bar of the frame of the table.

My invention consists of a horizontal bar D which is provided with vertical lugs E and F at the ends thereof, the upper ends of said 40 vertical lugs being bent to form inverted U-shaped hooks E' and F' which extend over the upper edge of the frame bar C and downwardly against the inner surface of the same.

The lower end e of the vertical lug E is turned upwardly. Pivoted on the upturned end e of the lug E is a spindle G which is

provided with a slot to receive the upturned end e. A pivot pin G' which passes transversely through the spindle G and upturned end e of the lug E is provided to retain the 50 spindle G in place on the lug E, so that said spindle G can be swung upwardly as illustrated by broken lines in Fig. 1.

The lower end f of the opposite vertical lug F is provided with a U-shaped hook adapted 55 to receive and support the free end of the spindle G in a horizontal position.

The structure comprising my invention when in place upon the horizontal frame bar C of an operating table is free to be moved 60 horizontally thereon as desired.

When the spindle G is swung upwardly as shown by broken lines in Fig. 1, a spool of tape H, see Fig. 4, can be placed thereon, with ends of tape H' projecting therefrom, 65 so that by grasping a tape end H', tape can be removed from the spool and torn off as desired.

It will be obvious that spools of tape will be supported by my invention, and that the 70 same will be in convenient position when needed, and thereby prevented from rolling out of reach, or falling upon the floor, and being exposed to unsanitary conditions.

Having thus shown and described my invention so that others can utilize the same, 75 what I claim as new and desire to secure by Letters Patent is:

In a device of the class described, a plate, inverted U-shaped hooks on the upper edge 80 of said bar at each end thereof adapted to engage a suitable support and hold said bar in a horizontal position, a vertical lug on the lower edge at one end of said plate, a spindle rod pivoted on said vertical lug and adapted 85 to swing thereon, and a U-shaped lug on the lower edge of said plate adapted to receive the free end of said spindle, whereby said spindle is adapted to resist lateral strain thereon.

In testimony whereof I affix my signature.

WILLIAM KALTSCHMIDT.
